UNITED STATES PATENT OFFICE.

ERIK ANTON RUNDLÖF, OF STOCKHOLM, SWEDEN.

MEANS FOR REGULATING THE STROKE OF PUMPS.

1,055,086.

Specification of Letters Patent.

Patented Mar. 4, 1913.

Application filed January 10, 1910. Serial No. 537,307.

To all whom it may concern:

Be it known that I, ERIK ANTON RUNDLÖF, a subject of the King of Sweden, residing at Stockholm, in the Kingdom of Sweden, have invented new and useful Improvements in Means for Regulating the Stroke of Pumps, of which the following is a specification, reference being had to the drawing accompanying and forming a part hereof.

This invention relates to means for varying the length of stroke of pumps, especially for internal combustion engines, and more particularly to stroke varying devices of the said kind in which the pump piston or driven member is actuated by a reciprocating member supported and mounted so as to be able to oscillate about a center.

The object of the invention is to provide a stroke varying device of the said kind which is simple in construction and reliable in working, and the invention consists, chiefly, in that the varying of the pump stroke is effected by raising or lowering a supporting member for the actuating member, whereby the distance between the center of oscillation of the reciprocating member and its point of contact with the driven member, counted in the direction of movement of the said latter member, is correspondingly varied.

The invention further comprises the constructions and combinations of parts hereinafter more particularly described.

In the drawing, Figure 1 is a side elevation of one embodiment of my invention. Fig. 2 is a similar view of a modified construction.

Referring to Fig. 1 of the drawing, *a* is the piston of a fuel pump *p*, and *b* is the member actuating the said pump piston, said member being adapted to swing about a fulcrum *c* on a member *o* movable toward and away from the piston *a*, for instance a slide movable in guides (not shown) and actuated by a cam or otherwise. The actuating member *b* is supported and guided by a member *d* supported in such a manner that it may be raised or lowered, for instance by a lever *m* and a spring *n*, as clearly shown in the drawing. The pump piston *a* has an abutment surface *e* which in the embodiment shown extends at right angles to the direction of movement of the piston. At each stroke of the reciprocating member its forwardly tapering end strikes the surface *e* and presses the piston inward. When the member *d* takes up the position shown in the drawing, the line which may be supposed to connect the center of oscillation of the reciprocating member *b* with the end *f* thereof coincides with the direction of movement of the pump piston, in which case the length of stroke is the greatest possible. If, on the contrary, the member *d* is lowered so that the member *b* is caused to swing downward by gravity, always in contact with the member *d*, the projection of the said line on the direction of movement of the pump piston, and thereby the length of stroke of the latter, is decreased.

The member *b* may be shaped otherwise at the end than described, and supported directly by spring *n* and lever *h* for instance such as shown in Fig. 2, where the end *g* has the form of an arc which is eccentric in relation to the center of oscillation. In the swinging movement of the member *b* the different points on the surface of the arc *g* will contact with the abutment surface *e* of the pump piston *a* and on account of the eccentricity of the arc the variation of movement of the pump piston for a given swing of the member *b* will be greater than in the construction shown in Fig. 1, for the eccentricity of the arc is so constructed that for the same angular motion of the member *b* in Fig. 1 and in Fig. 2 the end of said member will recede farther off from the surface *e* in Fig. 2 than the above mentioned projection of the connection line in Fig. 1 decreases.

When the regulating device is used in engines having two or more cylinders, a pump with its operating members *b*, *c*, and *d*, is used with each cylinder, and the reciprocating members *b* corresponding to the different cylinders are all supported by a common member *m*. According to Fig. 1, this member is swing supported at *h* and connected by springs *n* to each separate supporting plane *d*. Preferably, the connection is adjustable, for instance by nuts *i*, as shown in the drawing. The turning of the member *m* may be effected by a common pendulum governor *k* driven by the engine. In engines having two or more cylinders, in which the supply of fuel takes place at different times, the regulating members *b* are driven in such a manner that they will operate the pump pistons at correspondingly different times. At each time one or more

of the members *b* will therefore be in contact with their corresponding pump pistons, while the other members *b* are free, *i. e.* out of contact with their pump pistons. When 5 a member *b* is in contact with its pump piston, the friction between the said members is so great that an adjustment of the member *b* from the governor cannot take place. In order that the members *b* retained by friction at the pump pistons shall 10 not prevent the free members *b* from being adjusted the springs *n* provide an elastic connection. It will be easily understood that the free members *b* are immediately adjusted 15 according to the position of the governor whereas those members *b* which are engaged by the pump pistons are not adjusted before they leave the same.

Finally, it should be noted that the arrangement described enables a convenient stopping of internal combustion engines having two or more cylinders. The stopping may be effected by simply pressing down the member *m* by hand, thus causing 20 all the sliding planes *d* to be swung downward sufficiently for causing all the members *b* to move out of action.

Finally, I wish it to be understood that the invention is not limited to use in connection with fuel pumps for internal combustion engines, for obviously it may be used for controlling pumps or other devices of any kind.

I claim:

55 1. In a pump, the combination of a piston, a member adapted to reciprocate toward and away from the said piston in substantially the same direction as the line of travel of the piston, an intermediate part 40 swingably connected to the said reciprocating member and adapted to contact with said piston, a movable supporting member for the said swingable part, and means for automatically adjusting the position of the 45 said supporting member in such a manner as to cause the swingable part to perform a swinging movement about its fulcrum, by which the pump stroke is correspondingly changed.

2. In a pump, the combination of a piston, 50 a member adapted to reciprocate toward and away from the said piston in substantially the same direction as the line of travel of the piston, an intermediate part swingably connected to the said reciprocating member and adapted to contact with said piston, a movable supporting member for the said swingable part, a governor, and a resilient connection between the said governor and the supporting member aforesaid. 60

3. In a pump, the combination of a piston, 65 a member adapted to reciprocate toward and away from the said piston in substantially the same direction as the line of travel of the piston, an intermediate part swingably connected to the said reciprocating member and adapted to contact with said piston, a movable supporting member for the said swingable part, a governor, and an adjustable connection between the said 70 governor and the supporting member aforesaid.

4. In a pump, the combination of a piston, 75 a spring acting on the said piston for moving it outward, a member adapted to reciprocate toward and away from the said piston in substantially the same direction as the line of travel of the piston, an intermediate pump-operating part swingably connected to the said reciprocating member and 80 adapted to contact with said piston, a movable supporting member for the said swingable part, and means for automatically adjusting the position of the said supporting member in such a manner as to cause 85 the swingable part to perform a swinging movement about its fulcrum, the coöperating abutment surfaces of the actuating part and of the pump piston being so arranged relatively to each other that, when the actuating part strikes the pump piston, the latter acts to press the former against its supporting member. 90

ERIK ANTON RUNDLÖF.
